RECORDING APPARATUS

Harold G. Johnstone, Chicago, and John C. Gates,
Downers Grove, Ill., assignors to Western Electric Company, Incorporated, New York, N. Y., a corporation of New York

Application March 11, 1932, Serial No. 598,156

30 Claims. (Cl. 164—113)

This invention relates to recording apparatus, and more particularly to an apparatus for inscribing information in statistical cards for use in tabulating systems.

5 It is an object of the present invention to provide a simple and economically constructed recording machine capable of operation at a high rate of speed.

In accordance with one embodiment, the invention contemplates the provision of a perforating apparatus for inscribing information in statistical record sheets wherein a group of keys having numbers corresponding to the value of the perforations in each row or column of a statistical record card is provided for setting up information to be perforated in the card. These keys are adapted to store information in a plurality of groups of relays and each key upon being operated automatically associates the entire group of 20 keys with a succeeding group of relays. There is provided one group of relays for each column of the record card and each group consists of a relay for each possible hole in that column. After the keys have been operated a number of 25 times corresponding to the number of columns of the record card, a punch controlling key may be actuated and the information stored in the relays will be automatically inscribed in the record card by a plurality of perforators without further 30 manual intervention, mechanism being provided whereby, while the perforators are inscribing information in one card, information for inscribing in a second card may be set up in the relays.

Means is also provided for setting up information in the device which will automatically be perforated in all succeeding cards until said means is rendered ineffective manually. This automatic operation of the perforating mechanism may be selectively controlled to perforate 35 information in all of the rows or columns of a card, to perforate information in some of the rows automatically while the other rows are perforated under manual control or to skip predetermined selected columns which it is not desired to have perforated, thereby providing great 40 flexibility of operation.

A complete understanding of the invention may be had by reference to the following detailed description thereof, when considered in 45 conjunction with the accompanying drawings, wherein

Fig. 1 is a fragmentary plan view of a mechanism embodying the features of applicants' invention;

50 Figs. 2 and 3 are longitudinal vertical sectional

views taken on the lines 2—2 and 3—3 of Fig. 1, respectively, in the direction of the arrows, showing the mechanism for automatically associating the keys with the groups of relays;

5 Fig. 4 is a fragmentary transverse vertical sectional view taken on the line 4—4 of Fig. 1 in the direction of the arrows showing other details of the mechanism shown in Figs. 2 and 3, a portion of the storage relays, and some of the details of the perforator actuating mechanism;

10 Fig. 5 is an enlarged fragmentary longitudinal vertical sectional view taken on the line 5—5 of Fig. 1 in the direction of the arrows showing some of the storage relays in detail and details of the perforator actuating mechanism;

15 Fig. 6 is an enlarged fragmentary longitudinal vertical view taken on the line 6—6 of Fig. 1 in the direction of the arrows showing additional details of the perforator actuating mechanism;

20 Fig. 7 is a fragmentary transverse vertical sectional view taken on the line 7—7 of Fig. 1 in the direction of the arrows showing some of the details of the actuating mechanism for associating the keys with the storage relays;

25 Fig. 8 is a fragmentary vertical sectional view taken on the line 8—8 of Fig. 1 in the direction of the arrows showing details of the controlling keys;

30 Fig. 9 is a fragmentary vertical sectional view taken on the line 9—9 of Fig. 3 in the direction of the arrows;

35 Fig. 10 is a circuit diagram showing schematically the electrical connections between the various parts of the apparatus;

40 Fig. 11 is an enlarged plan view of a combined alphabetical and numerical keyboard, a portion of which appears in Fig. 1 and which may be used when it is desired to perforate combinations of perforations in a row or rows of a statistical card to represent printed matter, and

45 Fig. 12 is a circuit schematic of the electrical connections running from the keys shown in Fig. 11 and when placed to the right of Fig. 10 with the lower portion of Fig. 12 adjacent the upper portion of Fig. 10 and when considered in conjunction with Fig. 10 shows all the circuit connections of the preferred embodiment of applicants' invention.

50 Referring now to the drawings wherein like reference numerals designate the same parts throughout the several views, particular reference being had to Figs. 1 and 8, the numeral 11 designates a base upon which the mechanism is supported. In the lower right hand corner of the base 11 (Fig. 1) there is shown a key box 12 55

from the top of which extend 15 keys having imprinted thereon reference characters indicating the particular function of the keys. These keys are designated P, S, BS and 0, 1, 2, 3, 4, 5, 6, 7, 8, 9, 11 and 12. The keys 1 to 9, 0, 11 and 12 are all exactly the same in construction and each of them upon being operated, will close an electrical circuit between three contacts individual thereto. The keys having the characters P, S, 12, 11, 0, 1, 2 and 3 control the operation of contact springs mounted upon the right side (Fig. 8) of the key box 12 and the keys having the characters BS, 4, 5, 6, 7, 8 and 9 control the operation of contact springs mounted on the left side (Fig. 8) of the key box 12. Since the construction and operation of all of the keys bearing numerals are exactly the same, only one of them will be described, namely the key associated with the numeral 12 which has been assigned reference numeral 13, and is shown in full in Fig. 8 positioned at the right of the figure. The key comprises a button 14, having a stud 15 fixed thereto which is slidably in an aperture 16 formed in a top plate 17 of the key box 12. The lower end of the key 13 is slidably positioned in an intermediate plate 18 and has a pin 19 extending through it which normally engages the underside of the intermediate plate 18 to prevent upward movement of the key beyond a predetermined position, a spring 20 being positioned between the button and the top plate 17 and surrounding the stud 15 for normally urging the key upwardly. The stud 15 has formed integral therewith a laterally extending contact actuating lug 26 which, upon depression of the key, will engage a contact spring 27 suitably mounted in an insulating block 28 to complete an electrical circuit between the spring 27 and a pair of cooperating contact springs 29 and 30, for controlling the operation of the mechanism. The key 13 is provided with a reduced portion 31 which normally enters an aperture 32 in a shiftable plate 33 slidably mounted in the key box 12. The shiftable plate 33 is normally urged to the left (Fig. 8) by a contractile spring 34, through a link 35 fixed to a lug 36 extending downwardly from the plate 33. However, under circumstances to be described hereinafter, plate 33 may be moved to the right (Fig. 8) due to the energization of an electromagnet 37, armature 38 of which is pivotally secured to the link 35, and will prevent the depression of the key 13 due to the moving of the aperture of the shiftable plate 33 out of registration with the reduced portion 31 of the key.

As pointed out hereinbefore, all of the keys are constructed in exactly the same manner and the shiftable plate 33 is common to all of the keys except the keys indicated by the letters P, S and BS which do not have the reduced portion 31 and which, upon their operation actuate only one electrical contact spring for completing an electrical circuit between itself and another contact spring mounted in a manner similar to the contact springs associated with the key 13 which has been described in detail. From the foregoing, it will be apparent that when the electromagnet 37 is energized, none of the keys bearing numerals can be depressed. The purpose of this arrangement will become apparent as the description progresses.

The keys in the key box 12 associated with the numbers and letters 12, 11, 0, 1, 2, 3, 4, 5, 6, 7, 8, 9, P, S, BS, have been assigned the reference numerals 13 and 43 to 56, respectively.

Referring to Fig. 10, it will be seen that the right hand contacts of keys 13, 43, 44, 45, 46, 47, 48, 49, 50, 51, 52, 53 and 56 are connected through conductors 57, 59, 61, 63, 65, 67, 69, 71, 73, 75, 77, 79 and 81 to brushes 58, 60, 62, 64, 66, 68, 70, 72, 74, 76, 78, 80 and 82, respectively.

The middle contacts of keys 13, 43, 44, 45, 46, 47, 48, 49, 50, 51, 52, and 53, and the right hand contact of key 55 are connected through a conductor 83 to one side of the winding of an electromagnet 84. The left hand contacts of keys 13 and 43 to 53, inclusive, 55 and 56 are connected through a conductor 85 to ground at 86. The purpose of these circuit connections will become apparent as the description progresses.

The brushes 58, 60, 62, 64, 66, 68, 70, 72, 74, 76, 78, 80 and 82 together with a brush 100 (Figs. 1, 4 and 10) are mounted upon a cross bar 101 of insulating material forming a part of a relay distributor carriage 102 comprising the cross bar 20 and a bracket 103. Rotatably mounted in each end of the bracket 103 (Fig. 4) is a pair of grooved rollers 104 and 105 which ride upon two tracks 106 and 107 extending upwardly from brackets 108 and 109, respectively, mounted upon plate 30 supporting side members 110 and 111, respectively, extending upwardly from the base 11. A pair of small U-shaped brackets 118 and 119 are provided normally to hold the grooved rollers 104 and 105 in place upon the tracks 106 and 107. From the foregoing it will be apparent that the carriage 102 may be moved to the right or left (Fig. 1) on the tracks 106 and 107 to move the brushes 58, 60, 62, 64, 66, 68, 70, 72, 74, 76, 78, 80, 82 and 100, in unison over a contact plate 120 35 mounted on the plate supporting side members 110 and 111.

The embodiment of the machine being described in detail is of the type adapted to perforate a record card having 45 columns of 12 holes each 40 it being understood, however, that by simply increasing the number of the various parts of the apparatus hereinbefore described and to be described hereinafter, a card having any desired number of columns and any desired number of 45 possible perforations per column, could be perforated. Since a perforating mechanism adapted to perforate a 45 column card has been selected for illustration, the plate 120 which is formed of insulating material has embedded therein 45 50 columns of contact pins 121 there being a pin in each column for cooperation with each of the brushes 58, 60, 62, 64, 66, 68, 70, 72, 74, 76, 78, 80, 82 and 100 and the brushes, in being moved in unison across the contact plate 120 will engage the 55 contact pins 121 associated therewith.

A driving bar 122 (Figs. 2, 4 and 7) is secured to a downwardly extending portion of the bracket 103 and upon being actuated by mechanism hereinafter described, will advance the relay distributor carriage 102 step-by-step across the contact plate 120 to bring the brushes supported thereby successively into engagement with all of the contact pins 121 associated therewith.

Referring now to Fig. 10, it will be seen that 65 each of the contact pins 121 with the exception of the horizontal rows associated with the brushes 82 and 100 is connected to one side of the winding of a relay 123 individual thereto, these relays being positioned beneath the base plate 11. 70

The relays 123 which as pointed out hereinbefore are mounted beneath the base 11, are supported upon a sub-base plate 124 (Figs. 4 and 5) secured to the base plate 11 by supporting members 125. Only a few of the relays are shown, but 75

it will be understood that they are all of substantially the same construction, and that there is, as pointed out hereinbefore, one associated with each contact 121 on the contact plate 120, except the horizontal rows of contacts 121 associated with the brushes 82 and 100. Extending upwardly from the sub-base plate 124 are a plurality of metallic bars 126 which support the relays. The relays 123 are mounted on either side of the metallic bar 126 and are arranged in rows along the sides of the bar so that some of the parts which make up the separate relays are common to two of the relays directly opposite each other on the bar 126.

Since there are 45 columns of contacts on the contact plate 120, there will be 45 columns of relays supported upon 23 metallic bars 126. For the sake of simplifying the disclosure, only two rows of relays will be described.

Mounted upon opposite sides of the metallic bar 126 is a pair of plates 127 extending the length of bar 126 which have upwardly extending projections 128. There are two projections for each relay and since there are 12 relays in each of the 45 columns, there will be 24 projections 128 formed on the plate 127, one of which will act as the core of the relay winding and the fixed contact of the relay, and the other one of which serves as a return path for the magnetic flux when the relay is energized. The plates 127 of magnetic material 30 have strips of insulating material 129 extending along the surface thereof away from the metallic bar 126 upon which are mounted a plurality of T-shaped movable, magnetic contact members 133 (see Fig. 5), capable of being attracted into engagement with the fixed contacts on the projections 128 upon energization of a winding 130 of the relay. The windings 130 are insulated from the bars 126 by sheets of insulating material 131 and 132 which are suitably apertured to permit the positioning thereof upon the upwardly extending projections 128 of the plates 127. The T-shaped contact members 133 are provided with terminals 134 at their lower extremities whereby they may be connected in the electrical circuit, and upon energization of any relay winding 130 the movable contact member 133 will be attracted to complete a circuit from the movable contact member 133 through the projection 128 which serves as a core of the relay, and through the plate 127 to the bar 126. Insulated conductors 135 and 136 are connected to opposite ends of the windings 130 at the lower sheet 132 of insulating material and passed through apertures 137 in the strips of insulating material 129 for connection to other parts of the apparatus and the plates 127 are connected to ground at 138 (Fig. 10). The conductors 135 connect one side of the winding of each of the relays (Fig. 10) to the contacts 121 associated therewith, and the conductors 136 are connected to a common conductor 139 (Fig. 10).

Each time one of the keys in the key box 12 is operated, it will connect ground from 86 through the conductor 85 to its associated brush on the relay distributor carriage 102 and will simultaneously connect ground through the conductor 83 to one side of the winding of the electromagnet 84 (Figs. 2 and 10) the other side of the winding of which is connected through conductors 150 and 151 to a fixed contact 152 which will be engaged by a movable contact 153 while information is being put into the machine due to the operation of a part of the mechanism to be described hereinafter and since the movable contact 153 is connected to grounded battery at 154 the electro-

magnet 84 upon the operation of any key in the key box 12 will be energized.

Energization of the magnet 84 will attract its armature 156 to which there is attached a link 157, the other end of which is pivoted to a T-shaped lever 158. The electro-magnet 84 is mounted on a depending portion 159 of the track 107, and its armature 156 is also pivoted to this portion of the track as shown in Fig. 2. The T-shaped lever 158 is normally urged to the right (Fig. 2) about a pivot pin 162 secured to the track 107 by a coil spring 160 secured to a second downwardly extending portion 161 of the track 107. Also oscillatable about the pivot pin 162, is an escapement cam 163 having a pin 164 secured thereto and extending into an aperture 165 in the T-shaped lever 158. A coil spring 166 secured to a downwardly extending portion of the escapement cam 163 normally urges the cam in a counterclockwise direction into engagement with notches 167 formed on the underside of the driving bar 122 which is normally urged to the left (Fig. 2) by a spiral spring 168 secured to the right end of the driving bar 122 at 169. The spiral spring 168 is enclosed in a housing 170 and is mounted upon a bracket 171, the support for which will be described hereinafter. The left arm (Fig. 2) of the T-shaped lever 158 has a slot 171 formed therein in which a pin 178 secured to an oscillatable stop member 179 is slidable, the oscillatable stop member 179 being pinned to the track 107 at 180. A pair of contact springs 181 and 182 are associated with the stop member 179 and when the stop member is in normal position as shown in Fig. 2, contact will be made between the contact springs 181 and 182 to complete an electrical circuit to be described more in detail hereinafter.

From the foregoing, it will be apparent that each time one of the numeral bearing keys in the key box 12 is operated and released, the driving bar 122 will step forward one notch due to the energization and release of the electromagnet 84, removing the escapement cam 163 from the notch 167 with which it is associated. At the same time stop member 179 will be moved up into one of the notches 167 to prevent the driving bar 122 from moving until the key operated is released. As the stop member 179 moves upwardly it will break the electrical circuit between the contacts 181 and 182.

When the key which has been operated is released, the electromagnet 84 will be deenergized and the driving bar 122 will be permitted to move one step to the left due to the fact that the stop member 179 will be removed from the notch 167 with which it is associated just before the edge of the pawl 185 passes the lower edge of the notches 167 to enter the notch adjoining the one from which it was removed upon energization of the electromagnet 84.

In order to permit the operation of the driving bar 122 in a reverse direction in the event that a wrong number has been set up on the keys bearing numerals, the back space key is provided. This key differs from the other keys in the group in that it is connected by a flexible connection 184 commonly known as a "Bowden wire" to a back space pawl 185 to move the pawl in a counterclockwise direction around a pivot pin 186, upon which it is pivoted, which pin is secured to an oscillatable lever 187 which is normally urged in a counterclockwise direction about a pivot 188 by a spring 189. Upon the depression of the back space key 56 the flexible connection which is connected directly hereto, will first ro-

tate the back space pawl 185 about its pivot 186, and continued downward movement of the key will force the oscillatable lever 187 in a clockwise direction about its pivot 188 to step the actuating bar to the right (Fig. 2) one notch.

Each time a numeral bearing key in the key box 12 is operated, it will be apparent from the description thus far that the relay distributor carriage 102 will be stepped one space to the left (Figs. 1 and 2) after energizing a relay 123 associated with the key operated through one of the contacts 121 and the brush associated with the particular key actuated. Thus, upon the keys in the key box 12 being actuated manually, the relay distributor carriage will step across the face of the contact plate 120 energizing the relays associated with the keys operated in all of the columns until the keys have been operated 45 times (this being the number of holes which it is desired to perforate in the card) when the relay distributor carriage will have passed over all of the columns of contacts to store in the relays the information which it is desired to perforate into a record card. From the description of the circuit connections, it will be apparent that when the space key 55 is operated the electromagnet 84 will be energized to advance the relay distributor carriage 102 one space without storing any information in the relays 123 associated with the row of contacts 121 with which the brushes of the relay distributor are at that time associated since the space key is not connected to any of the brushes associated with the contacts 121.

35 Movable with the relay distributor carriage 102 and mounted upon the extreme left end of the driving bar 122 (Figs. 1 and 2) is a contact operating mechanism 195 which comprises a plunger 196 slidable in an aperture 197 formed in a block 198 and engaging the lower end (Fig. 1) of a lever 199 pivoted intermediate its ends upon a pin 200 mounted in the driving bar 122. The lever 199 carries at its rear end (Fig. 1) a contact operating roller 201 for engaging a group of contacts designated generally by the numeral 202 (Figs. 1 and 10) in such a manner as to cause a contact 203 to engage a contact 204 when the lever 199 is moved in a counterclockwise direction (Fig. 1), to overcome the resiliency of the contact spring 203. The contact operating mechanism 195 moves with the relay distributor carriage 102 and upon the relay distributor carriage reaching its extreme left position, the plunger 196 will engage an abutment 207 on a punch distributor carriage 208, whereupon the lever 199 will be rocked upon its pivot to move the contact 203 into engagement with its associated contact 204 (Fig. 10). A portion of the relay carriage 102 together with the contact operating mechanism 195 is shown in dotted lines in Fig. 1 in the extreme left position of the relay distributor carriage 102.

The punch distributor carriage 208 as shown in Figs. 1, 3 and 4, comprises a bracket 209 carrying at its ends grooved rollers 211 and 212. The rollers 211 and 212 are mounted upon the bracket 209 in the same manner that the rollers 104 and 105 are mounted upon the bracket 103, and the roller 211 travels upon the track 106 together with the roller 104, whereas the roller 212 travels upon a track 213 the construction of which is exactly the same as that of the track 107, a U-shaped bracket 214 being provided to maintain the roller 212 in position upon the track 213. A

punch distributor driving bar 220 is provided for moving the punch distributor carriage 208 to the right or the left in a manner similar to the movements of the relay distributor carriage 102 for moving a set of brushes 221 over the contacts 121 to take the information stored in the relays associated with the contacts 121 therefrom and control the operation of a punching mechanism in accordance with that information.

The plunger 196 and the abutment 201 are so positioned that when the brushes on the relay distributor carriage 102 and the brushes on the punch distributor carriage are in a position upon the contact plate 120 where they are spaced apart less than the distance between two rows of contacts 121, the plunger 196 will be actuated to move the contact 203 into engagement with the contact 204.

The driving bar 220 for actuating the punch distributor carriage 208 is provided, as shown in 20 Figs. 1 and 3, with teeth 222 upon its upper surface and notches 223 upon its lower surface and supports, adjacent its right end Fig. 3, the bracket 171 upon which is mounted the spiral spring 168 (Figs. 2, 3, and 7). The teeth 222 on the upper 25 surface of the punch distributor driving bar mesh with a gear 224 for driving the punch distributor driving bar to the right (Figs. 1 and 3), a spring motor 225 of a well known type being provided for normally tending to drive the punch distributor driving bar to the right. The spring motor 225 is mounted upon a side plate 226 of the punch mechanism which is indicated generally in Figs. 1 and 4 by the numeral 227.

The punching mechanism 227 comprises a group of 12 perforating pins 235 (Figs. 1, 4 and 5) mounted in guide plates 236 and 237 secured between side plates 238 and 239. The perforating pins 235 are slideable vertically in the guide plates 236 and 237 and each pin has associated therewith an interposer bar 240 which has its left end (Fig. 5) supported on the head of the perforating pin and its right end slideable in a cross member 241 mounted between the side plates 238 and 239, the interposer bars being provided with pins 242 to prevent movement thereof in a horizontal plane beyond a predetermined distance, and the cross member 241 being slotted at 243 so that it will support the interposer bars 240 but will permit a slight rocking movement thereof. Mounted upon suitable supports 244 extending between the side plates 238 and 239 and arranged in staggered relation are a plurality of electromagnets 245, (Figs. 1, 5, 6 and 10) one of which is associated with each of the interposer bars 240. Each of the interposer bars 240 is provided with a lug 246 adapted to enter an aperture in an armature 247 of its associated electromagnet 245, so that upon energization of the electromagnet 245 associated with any interposer bar, that bar will be released for movement to the left (Fig. 5) the bars as shown in Figs. 1 and 5 being in their normal or extreme right hand position.

Each of the interposer bars 240 has a notch 253 cut in the left end thereof (Fig. 5) to permit the downward movement of a punch actuating ram 254 without operating the perforator pin 235 associated with the interposer bar 240 when the ram is moved downwardly, provided the interposer bar is in its normal position as shown in Fig. 5. However, upon energization of an electromagnet 245 the interposer bar associated therewith may be moved to the left by a spring 255 associated therewith to move the interposer bar into position to be driven downwardly by the 75

punch actuating ram 254 when the ram is actuated. The spring 255 is normally in the position shown in Fig. 5. However, the spring has its inner end secured to a shaft 256 and will tend to resiliently drive the bar to the right or the left with the shaft 256 which at predetermined points in the cycle of operation of the punch is rotated in opposite directions (see Fig. 6).

In Figs. 1, 5 and 6 there are shown the cams for operating the punch actuating ram 254 and the shaft 256. The ram 254 is common to all of the perforating pins 235 and their interposer bars 240 and extends across the space enclosed by the side plates 238 and 239 to which it is pivoted as shown at 251 (Fig. 5) and is operated by a link 258 pivoted to the right end of the ram and having its other end pivoted to an oscillatable cam lever 259. The cam lever 259 may be rocked about a pivot 260 upon the rotation of a shaft 261 carrying a cam 262 having a groove 263 formed therein in which rides a cam roller 264 mounted upon the right end (Fig. 5) of the lever 259. The shaft 261 carries a second cam 270 (Fig. 6) having a cam groove 271 formed therein in which rides a cam roller 272 positioned upon the end of a cam lever 273 pinned to the shaft 256. The cam grooves 263 (Fig. 5) and 271 (Fig. 6) are so formed that their associated cam levers will be moved through the following cycle each time the shaft 261 is rotated. Simultaneously, the cam lever 273 will be rocked in an anti-clockwise direction to store energy in the springs 255 tending to advance the interposer bars 240 to the left, and one of the electromagnets 245 actuated, the interposer bar 240 associated with that particular electromagnet will be advanced to the left by its spring 255, and shortly after the arrival of one of the interposer bars over its associated punch, the cam 262 will actuate the cam lever 259 to drive the punch actuating ram 254 downwardly and then upwardly. After the punch actuating ram 254 reaches its uppermost position the shaft 256 will be rocked by the cam 270 in a clockwise direction and any interposer bar which has been advanced to the left will be retracted to the position shown in Fig. 5.

Secured to the underside of the ram 254 is a perforator pin stripping plate 278 which moves with the ram and will retract any perforating pin, which has been driven downwardly, back to its normal position as shown in Fig. 5 when the ram is elevated.

After all of the information to be perforated in a record card has been set up by operating successive keys in the key box 12, the punch key 54 may be operated to cause the brushes 221 on the punch distributor carriage 208 to be associated with the contacts 121 for controlling the operation of the electromagnets 245. The operation of the punch key 54 (Fig. 10) will connect ground at 279 through the contacts of the key, a conductor 280 (Fig. 10) to one side of the windings of an electromagnet 281, the other side of the winding of which is connected to a grounded battery at 282, and from the conductor 280 through a branch conductor 283 to a front contact 284 and to one side of the winding of a relay 285, the other side of the windings of which are connected to a grounded battery at 154. The electromagnet 281 as shown in Figs. 3 and 10 will attract its armature 286 which has pivoted thereto a link 287. The electromagnet 281 is mounted upon a depending portion 292 of the track 213, and the link 287 is normally urged to the left (Fig. 3) by a contractile spring 293, one end of which is secured

to the depending portion 292, and the other end of which is fixed to a projection 294 formed on the link 287.

An escapement mechanism comprising a pair of pawls 295 and 296 is provided for advancing the punch distributor driving bar 220 to move the punch distributor carriage 208 across the face of the contact plate 120. The pawl 295 is pivoted on the depending portion 292 of track 213 at 297 and is normally urged about its pivot in a clockwise direction by a contractile spring 298, and the pawl 296 is pivoted on an oscillating lever 299 at 300 in the manner shown in Figs. 3 and 9, the pawl 296 being normally urged to rotate about its pivot in a clockwise direction by a contractile spring 301. The pawls 295 and 296 are provided with cam slots 302 and 303 adapted to be engaged by camming pins 304 and 305 mounted upon cam levers 307 and 308, respectively. The cam levers 307 and 308 are pivoted upon small stud shafts 309 and 310 secured in the depending portion 292 and are pivoted at their lower end to pivot pins 311 and 312, respectively, on the link 287, so that when the electromagnet 281 is energized to attract its armature 286, the camming levers 307 and 308 will be rocked about their pivots 309 and 310, respectively, to cam the pawls 295 and 296 out of engagement with the punch distributor driving bar 220 to permit it to be driven to the right by the spring motor 225.

The oscillating lever 299 (Figs. 3 and 9) is pinned to a stud shaft 313 journaled in the depending portion 292 of the track 213 and the shaft 313 has pinned to the opposite end thereof a cam lever 314 carrying a cam roller 315 adapted to be driven by a cam 316 keyed to the shaft 261.

The punch distributor driving bar 220 has a pin 321 positioned thereon which, when the punch distributor driving bar is moved to its normal position as shown in Figs. 1 and 3 will engage a slide bar 322, slidably mounted upon supporting pins 323 positioned upon plates 324 supported by the track 213, and will move the slide bar to the position shown. The slide bar when moved to the position shown in Fig. 3 will be maintained in that position by a spring pressed center stop 325, mounted on the left hand plate 324, engaging a notch 326 in the lower edge of the slide bar.

When the electromagnet 281 is energized to permit the spring motor 225 to drive the punch distributor driving bar 220 to the right (Fig. 3) the slide bar 322 will remain in the position shown until the driving bar nears the end of its travel to the right, at which time the pin 321 will engage an arm 327 of the slide bar to shift the bar to a position where the center stop 325 will engage a notch 328 to hold the bar stationary until it is engaged by the pin 321 near the end of the travel of the pin to the left (Fig. 3).

The slide bar 322 carries a pair of pins 329 and 330 of insulating material, which when the slide bar is moved to the right engage contact springs 331 and 332, respectively, to move them to the right and to cause the spring 331 to engage a cooperating contact spring 333 and to cause the spring 332 to disengage from a cooperating contact spring 335. The contact springs 331 and 333 are mounted in a block 334 of insulating material positioned on a downwardly extending portion of the track 213 and the contact springs 332 and 335 are positioned in a second block 336 of insulating material also mounted on a portion of the track 213.

The contact springs 331 and 333 are normally out of engagement and the contact springs 332

and 335 are normally in engagement with each other so that when the slide bar 322 is moved to its right hand position (Fig. 3) a circuit will be made between contacts 331 and 333 and a circuit 5 will be broken between contacts 332 and 335. When the slide bar is in its left hand or normal position, the contacts 332 and 335 will connect ground at 337 (Fig. 10) through a conductor 338 to a back contact 339 of relay 285. Thus when 10 the electromagnet 281 is momentarily energized, the relay 285 will also be energized and the punch distributor driving bar 220 will be moved to the right due to the completion of the locking circuit of relay 285 through back contact 339 until contact 15 springs 332 and 335 are disengaged at the end of the travel of the driving bar to the right (Fig. 3), at which time the pin 321 will engage the arm 327 to shift the slide bar 322 to the right and break the locking circuit by moving the contact 20 spring 332 out of engagement with contact spring 335.

Simultaneously with the breaking of the locking circuit to the electromagnet 281, the contact 25 spring 331 will be moved into engagement with contact spring 333 which is connected to one side of a motor 356 which drives the shaft 261. The other side of the motor 356 is connected to one side of a current supply line through a conductor 357 and the contact spring 331 is connected 30 through a conductor 358 to the other side of the current supply line.

A contact actuating pin 348 is mounted upon the punch distributor driving bar 220 in a position where it will not engage the upwardly extending 35 portions of the slide bar 322, but when the driving bar 220 is moved to its extreme right hand position (Fig. 3) the pin 348 will assume the position shown in dotted lines (Fig. 3) where it will engage a pivoted lever 349, pivoted to the track 213 at 350 and normally held in its upward position by the tension of contact springs 351 and 352 (Figs. 3 and 10).

The contact springs 351 and 352 are mounted in a block 353 of insulating material and are normally out of engagement with their cooperating contact springs 354 and 355, respectively, also positioned in the insulating block 353 which is secured to the track 213. The pivot lever 349 is so formed (Fig. 3) and the pin 348 is so positioned 40 upon the punch distributor driving bar 220 that the contacts 351 and 352 will be held out of engagement with the associated contacts 354 and 355 at all times except when the punch distributor driving bar is in a position where the brushes 45 carried by the punch distributor driving bar are in engagement with the last three columns of contacts 121 at the right hand side (Fig. 1) of the contact plate 120. The contact 351 (Fig. 10) is connected to ground at 361. The contact 354 is connected through a conductor 362 to the conductor 83 running to the electromagnet 84. The contact 352 is connected to grounded battery at 363 and the contact spring 355 is connected 50 through a conductor 364 to the conductor 150.

A card supporting table 370 (Fig. 1) adapted 55 to receive a card to be perforated is supported between the side plates 238 and 239, and after information has been stored in the relays 123, the card may be positioned upon the table 370 60 where it will, upon operation of the punch key, have its right hand edge engaged by a card feed lever 371 (Figs. 5 and 7) pivoted upon a bracket 372 at 373, and normally urged downwardly, being of resilient material. The bracket 372 travels 65 with the punch distributing bar 220 to which it is

secured, and moves the card feed lever 371 across the card supporting table 370 wherein there is provided a groove 374 (Figs. 1 and 7) in which the card feed lever 371 travels and into which the card feed lever tends to move upon passing over the right hand edge of the card (Fig. 1). When the card is positioned upon the card supporting table 370 and the punch distributor driving bar moves to the right (Fig. 1) the card feed lever 371 will meet the left end of the card and 10 slide over it until the card feed lever reaches its extreme right position where it will drop off the card into the groove and as the punch distributor driving bar is driven to the left will advance the card under the punches 235 in a step-by-step 15 motion. The card supporting table is provided with an aperture 375 (Fig. 5) associated with and positioned directly beneath each of the perforating pins 235. These apertures serve as dies and a card being advanced under the punches 235 20 will be perforated as it moves step-by-step thereunder.

In the event that it is desired to perforate constant information in predetermined columns of a plurality of record cards, there has been provided 25 a group of gang punching keys 380 (Fig. 1) for controlling such an operation. There is provided one gang punch key 380 for each column of perforations on the record card, and these keys which may be of any known type that will lock in either 30 their actuated or unactuated positions are provided with two pairs of electrical contacts 381 and 382, and 383 and 384 (Fig. 10).

Since all of the keys 380 are of exactly the same construction and are connected in a similar manner to their respective contacts 121 on the contact plate 120, only one key will be described. The contact 381 is connected through a conductor 385 to its associated contact 121 in the top row of contacts; the contact 382 is connected 40 through a conductor 386 to ground at 387; the contact 383 is connected through a conductor 388 to grounded battery at 389, and contact 384 is connected through a conductor 390 to a fixed 45 normally made contact 391 associated with a relay 392.

There is provided one relay 392 for each group of relays 123. The relays 392 are of a construction similar to that of the relays 123 in that they are mounted upon the common plates 127 and 50 additional projections 128 are provided to act as the core of the relays 392 and to serve as return paths for the magnetic flux when the relays are energized. However, the circuit connections to the relays 392 differ from the relays 123 in 55 that their armatures 394 do not serve as contacts, but actuate contacts 393 breaking contact between the contacts 393 and the fixed contacts 391 upon energization of their associated relays 392. The conductor 390 is also connected to the 60 common conductor 139 so that any relay 123 which is operated in a row in which a key 380 is operated will have grounded battery connected to one side of its winding until the key 380 is moved to its inoperative position. Each of the 65 relays 392 has its contact 393 connected to one side of its winding, and the same side of the winding of the relay is connected to grounded battery at 395, whereas the other side of the winding of the relay is connected through a conductor 396 to the contact 121 associated with the key 380 and positioned in the bottom row of contacts 121.

The brush 221 on the punch distributor carriage 208 associated with the bottom row of contacts 75

121 is longer than the other brushes 221, and when the brushes associated with the upper rows of contacts are engaging the extreme left hand row of contacts, the bottom brush will be engaging the next to the last row of contacts to the left (Fig. 1). This bottom brush is connected through a conductor 401 to a right hand back contact 402 of the relay 285 which contact is normally in engagement with a right hand movable contact 403 connected to ground at 154. A movable contact 404 of the relay 285 is connected to grounded battery at 154, and normally engages a fixed contact 405 which is connected through a common conductor 406 to one side of the windings of all of the electromagnets 245, the other side of the windings of which are connected through a plurality of conductors 407 to the brushes 221 on the punch distributor carriage 208.

It is believed that a clearer understanding of the invention will be had from a detailed description of the mode of operation of the various elements heretofore described. To facilitate the description of the operation of the mechanism an explanation thereof will be given in connection with the perforating of a record card into which it is desired to perforate certain information and it will be assumed that it is desired to perforate in the first to the twelfth column of the record card the perforations representing the numerals 12, 11, 0, 1, 2, 3, 4, 5, 6, 9, 8, 7 respectively, to leave unperforated the thirteenth to twenty-fifth columns of the record card and to set the numbers 3, 4, 8 and 9 in the twenty-sixth, twenty-seventh, twenty-eighth and twenty-ninth columns respectively, not only of the first card to be perforated but of a group of succeeding cards, and that it is desired to leave the thirtieth to forty-fifth rows, inclusive, of the card unperforated. In order to accomplish this the machine should be brought to normal as shown in Fig. 1 and then keys 13, 43, 44, 45, 46, 47, 48, 49, 50, 53, 52, and 51 should be operated in succession and in the order named and thereupon the space key 55 should be operated thirteen times. After the space key 55 has been operated thirteen times, the keys 47, 48, 52, and 53 should be operated and the keys 380 associated with the twenty-sixth, twenty-seventh, twenty-eighth and twenty-ninth columns should be operated at any time prior to the operation of the punch key 54, and the space key 55 should then be operated sixteen times in succession.

When the key 13 is operated it will complete a circuit from ground at 86 through the conductor 85, contact 30, contact 29, conductor 83 to the winding of the electromagnet 84, which will be energized due to the fact that the other side of its winding is connected through the conductors 150 and 151, contacts 152 and 153 to grounded battery at 154. Ground will also be connected from contact 27 to conductor 57 and brush 58 to contact 121 in the second row from the top (Figs. 1 and 10) of the contact plate 120 and thence through conductor 135 to the winding of relay 123 associated with the digit 12 to energize the relay since the other side of its winding is connected through conductors 139 and 390, and contacts 391 and 393 to grounded battery at 395. Thus the relay 123 associated with the digit 12 will attract its armature to complete a holding circuit from grounded battery at 395, contacts 393 and 391, conductor 390, common conductor 138 through the windings of the relay to its armature, and thence through the projections 128 to the plate 127 which is connected to ground at 138. The relay 123 associated with the number

12 will therefore be locked up under control of the foregoing circuit until the relay 392 is subsequently energized to break the contact between contacts 393 and 391. A similar circuit will be completed for each of the keys 13 and 43 to 53 as they are actuated in the order named hereinbefore; that is, as hereinbefore described the relay associated with the number 12 will be locked up for the first row of contacts 121 at the right hand side of the contact plate 120 simultaneously with the energization of the electromagnet 84. The electromagnet 84 which is slower to act than the relays 123 upon being energized over the hereinbefore described circuit will attract its armature 156, causing the pawl 163 to be drawn out of engagement with the notch 167 with which it is associated, and will permit the spring 168 to move the relay distributor driving bar 122 to the left (Fig. 2) one notch since the pawl 179 will also be moved upwardly into one of the notches 167 to prevent movement of the bar 122 more than one step. The movement of the bar 122 one step to the left (Figs. 1 and 2) will bring the brushes mounted upon the bar into engagement with the second row of contacts 121 on the contact plate 120. When the key 43 is operated, similar circuits will be completed to lock up the relay 123 associated with the number 11 in the second row of contacts 121 on the plate 120. As the keys 44, 45, 46, 30 47, 48, 49, 50, 53, 52 and 51 are operated in the order named the relay distributor carriage 102 will be stepped across the contact plate 120 from right to left (Fig. 1) to bring the brushes mounted thereon successively into association with the 35 columns of contacts 121, and will lock up the relays representing the numbers carried by the keys 13 and 43 to 53 in the order in which the keys were enumerated hereinbefore.

Since it is desired to leave the card imperforate in the 13th to 25th inclusive rows of possible card holes, the space key will be operated thirteen times and upon its operation will complete the following circuit: from ground at 86 over conductor 85 through the contacts of the key 55, conductor 83 to the windings of the magnet 84, which will be energized thirteen successive times and will move the relay distributor carriage 102 and associated brushes over the contacts 121 in the 13th to 25th rows, inclusive, of possible perforations in 50 the record card without energizing any of the relays 123 associated with those particular rows.

When the brushes mounted on the relay distributor carriage 102 are in contact with the 26th row, keys 47, 48, 52 and 53 may be operated to 55 complete circuits similar to those described hereinbefore, whereupon the keys 380 which are associated with the 26th, 27th, 28th and 29th rows may be moved to their actuated positions where they will complete circuits from ground at 387 through the contacts 382 and 381, conductors 385 to the contacts 121 on the contact plate 120 associated with the 26th, 27th, 28th and 29th rows, and circuits will be completed from grounded battery at 389 through the conductor 388, contacts 383 and 384, conductors 390 to the common conductors 139 associated with the relays 123 which are associated with the contacts in the 26th, 27th, 28th and 29th rows of contacts 121 on the contact plate 120, thereby to hold energized any relays which have previously been energized. In the problem selected for illustration, there are the relays associated with the digits 3, 4, 8 and 9, over circuits independent from those controlled by the relays 392 so that the relay 75

energized in a group associated with an operated gang punch key 380 will not be deenergized during the punching operation. Similar circuits will be completed upon operation of any of the gang punch keys 380, and these keys may be operated immediately after the keys in the key box 12, but preferably are operated after information for an entire record card has been set up.

If in the particular group of cards which are to be perforated, the 30th to the 45th rows inclusive, are to have no perforations therein, the gang punch keys 380 for those rows may be moved to their actuated positions, thus to cause the relay distributor carriage 102 to skip over these rows automatically. The operation of any gang punch key or group of gang punch keys 380 will complete a circuit from ground at 387 through the contacts 382 and 381, conductor 385, contact 121 associated with that particular gang punch key 380, brush 100, a conductor 400 interconnecting brush 100 and the contact 181, through the contacts 181 and 182, the windings of electromagnet 84, conductors 158, 151, contacts 152 and 153 to grounded battery 154, thereby to cause the operation of the electromagnet 84 each time the brush 100 engages a contact 121 which has been grounded due to the operation of its associated gang punch key 380. This operation will be caused due to the fact that the pawl 179 in returning to normal position will move the contact 181 into engagement with the contact 182, and since the pawl 179 returns to the position shown in Fig. 2, after each operation of the electromagnet 84, if gang punch keys 380 associated with successive rows of contacts 121 are in their actuated position, the electromagnet 84 will be operated a number of times in succession to permit the relay distributor carriage 102 to move its brushes rapidly over the columns of contacts 121 where the condition just outlined exists.

From the description of operation thus far, it will be apparent that the relay 123 associated with the first row of contacts at the right of the contact plate 120 and representing the digit 12 has been locked up to hold ground on its associated contact. In like manner relay 123 associated with the contact 121 in the second row of contacts from the right of the contact plate 120, representing the digit 11 has been locked up to connect ground to its associated contact 121, the relays 123 representing the digits 0, 1, 2, 3, 4, 5, 6, 9, 8 and 7, and connected to the contacts in the 3rd to 12th rows inclusive of the contacts 121, have also been locked up, no relay associated with the 13th to 25th rows of contacts on the contact plate 120 has been locked up, the relay 123 associated with the digits 3, 4, 8 and 9 in the 26th, 27th, 28th and 29th rows of contacts respectively have been locked up to place ground on their associated contacts, and no relays 123 associated with the 30th to 45th rows of contacts 121 have been energized. However, the relay distributor carriage 102 will have been advanced over the contact plate 120 to carry all of the brushes mounted thereon past the extreme left hand row of contacts 121 on the contact plate 120 and in moving to this position will have caused the plunger 196 to engage the abutment 207 and thereby to make contact between the contacts 203 and 204 to prevent the operation of any key in the key box 12 due to the completion of the circuit from ground through the contacts 204 and 203 to the windings of the electromagnet 84, the other side of the windings of which are connected to grounded battery. The closure of these

contacts occurs every time the brushes on the relay distributor carriage 102 are within two columns of the brushes carried by the punch distributor carriage 208 to prevent the operation of any of the keys in the key box 12 when the punches are close enough together to cause a possible error in the setting up of a problem to be perforated.

If a wrong number has been set into the relays 123, the back space key 56 may be operated to mechanically drive the relay distributor carriage backward through the operation of the back space pawl 185 which will first be moved into engagement with the notches 167 on the relay distributor driving bar 122, and will thereafter be moved to the right (Fig. 2) to step to carriage back one space. Simultaneously with this mechanical movement of the carriage to the right (Figs. 1 and 2) the back space key will complete a circuit through its contacts from ground at 86 (Fig. 10) 20 through brush 82, and the contact 121 with which the brush is associated to the relay 392 associated with the row in which the wrong information has been stored, thereby to momentarily actuate the relay 392, causing a break between the contacts 391 and 393 which will automatically release any actuated relay 123 due to removal of grounded battery from one side of the winding thereof by the breaking of contact between contacts 391 and 393.

A card in which it is desired to perforate the information stored in the relays 123, may now be placed upon the table 370 from which it will be picked up and advanced step-by-step under the perforating pins 235 by the card feed lever 371.

In order to start the punching operation, the key 54 should be operated. The operation of key 54 will connect ground from 279 through the contacts of the key, conductor 280, to the winding of electromagnet 281, the other side of the winding of which is connected to grounded battery at 282, and ground will also be connected from the contacts of the key through the conductor 280, a branch conductor 283 to the winding 45 of relay 285, the other side of the winding of which is connected to grounded battery at 154. The energization of the electromagnet 281 over the circuit just described will cause it to attract its armature, thereby to remove the pawls 295 and 296 from the notches formed on the under side of the punch distributor driving bar 220, allowing the spring motor 225 to drive the punch distributor driving bar 220 and the relay distributor driving bar 122 to the right (Figs. 1, 2 and 3) 55 since the coil spring 168 will have moved the relay distributor bar to the left to bring the plunger 196 into engagement with the abutment 207, and the abutment will serve to drive the relay distributor driving bar to the right with the punch distributor driving bar. The operation of relay 285 will disconnect grounded battery at 154 from one side of the winding of the electromagnet 84 due to the disengagement of contacts 152 and 153 and will also break the grounded battery connection to the contact 405 and conductor 406 to the electromagnets 245 and will remove the grounded connection at 154 through contact 403 and 402, conductor 401 to the brush 221, which engages the bottom row of contacts 121 on the contact plate 120. Furthermore, the momentary energization of the relay 285 will lock the relay in its energized position due to the completion of the circuit from grounded battery at 154 through the winding of the relay, contacts 284 75

and 338, conductor 338, contacts 332 and 335 to ground at 337. This circuit will be maintained through the contacts 332 and 335 until the punch distributor driving bar 220 reaches a position where the brushes on the punch distributor carriage 208 are in engagement with the extreme right hand row (Fig. 1) of contacts 121 on the contact plate 120. The energization of the relay 285 thereby prevents the operation of the electromagnet 84 and also prevents the release of any of the relays 123 which are locked up due to the removal of the ground connection from the brush 221. As the punch distributor carriage 208 reaches the end of its travel to the right (Figs. 1 and 3), the contact between contacts 332 and 335 will be broken due to the pin 321 (Fig. 3) moving the slide bar to the right (Fig. 3) and the pin 329 will engage the contact spring 331, thereby to move it into engagement with the contact spring 333 (Figs. 3 and 9). When the contact 331 engages the contact 333, it will complete a circuit through the motor 356, and the disengagement of contact spring 332 from contact spring 335 will remove ground from relay 285, thereby deenergizing it as the drive motor 356 rotates to drive the shaft 261 for the 45 punching cycles required.

The punch distributor driving bar 220, upon reaching the end of its stroke to the right (Figs. 1 and 5) will carry the card feed lever 371 to the right beyond the right edge of a card placed upon the card supporting table 370 permitting the card feed lever 371 to drop behind the edge of the card, and when the motor 356 starts to drive the shaft 261, the card will be advanced by the card feed lever 371. The shaft 261 upon being rotated by the motor 356 will reciprocate the pawl 296 through the cam 316 to drive the punch distributor carriage 208 step-by-step across the contact plate 120 (Figs. 3 and 9) and through the cam 270 will oscillate the shaft 256 to alternately store tension in the springs 255 in opposite directions. The punch distributor driving bar 220 as it carried the brushes on the punch distributor carriage 208 onto the third column of contacts 121 from the right of plate 120 (Fig. 1) in the movement of the distributor bar to the right, caused the contact 351 to engage the contact 354, and the contact 352 to engage the contact 355 due to the engagement of pin 348 with the lever 349 to connect ground through conductor 362 to one side of the winding of the electromagnet 84 and to connect grounded battery at 363 through the conductor 364 to the other side of the winding of the electromagnet 84. The energization of the electromagnet 84 will move the escapement cam 163 out of the notches 167 and will move the stop member 179 into engagement with the under side of the driving bar 122 which has the notches cut away at this point, so that when the punch distributor carriage 208 starts to travel to the left due to the operation of the driving pawl 296, the relay distributor carriage 162 will follow it until the brushes carried by the relay distributor carriage are in engagement with the first column of contacts at the right hand side (Fig. 1) of the contact plate 120, at which time the pin 348 will disengage from the lever 349 and the contact between contacts 351 and 354, and 352 and 355 respectively will be broken.

When the brushes 221 engage the first column of contacts at the right side of contact plate 120, the upper brush 221, (Figs. 1 and 10) will be connected to ground since the relay 123 representing

the digit 12 in that row has been locked up to connect ground through the conductor 135 to its associated contact and ground will therefore be transmitted through the conductor 407, associated with the 12 contact in the first column, to one side of the winding of the electromagnet 245 representing the digit 12, the other side of the winding of which is connected through the conductor 406, contacts 405 and 404 to grounded battery at 154, whereupon the electromagnet 245 representing the digit 12 will be energized to release its interposer bar 240 and since all of the interposer bars are at that time being urged to the left (Fig. 5) by their springs 255, the bar 240 associated with the digit 12 being released by its electromagnet 245 will be moved to the left, whereupon the cam 262 will drive the actuating ram 254 downwardly to drive the perforating pin 235 which is positioned under the interposer bar 240 associated with the digit 12 through the record card. Shortly after the actuating ram 254 has been driven downwardly it is retracted to its normal position as shown in Fig. 5 and carries with it the perforating pin 235 which was driven downwardly. In moving upwardly the actuating ram 254 will release the interposer bar 240, and since the spring 255 has had tension stored therein in the opposite direction by the cam 270, the interposer bar will be drawn back to its normal position. The electromagnet 245 associated with the retracted interposer bar will be deenergized due to the advancement of the brushes 221 out of engagement with the contacts 121 in the first column of contacts at the right side (Fig. 1) of the contact plate 120 and the interposer bar will be latched in its retracted position as shown in Fig. 5. Continued rotation of the shaft 261 will advance the record card to be perforated step-by-step under the perforating pins 235 and will perforate it in accordance with the information stored in the relays 123.

The lower brush (Figs. 1 and 10) mounted on the punch distributor carriage 208, will engage the lower row of contacts in each column successively, one row back of the rest of the brushes 221, and in so doing will operate the relay 392 (Fig. 10) associated with each row as the brush engages the contact 121 of that row due to the completion of the following circuit: From ground at 154 through contacts 403 and 402, conductor 401 to the bottom brush 221, through the contact 121, conductor 396 to the winding of relay 392 which is connected to grounded battery at 395. Energization of the relay 392 will cause its armature 394 to be attracted, thereby breaking the circuit through contacts 393 and 391, and removing grounded battery at 395 from one side of the windings of all of the relays 123 in that particular row. However, if a gang punch key 380 associated with one of the rows has been operated, the grounded battery at 389 will be connected through the contacts 383 and 384, conductor 390, through the common conductor 139 so that in a row where a gang punch key 380 has been operated the operation of the relay 392 will not affect the relays 123 in that row since they will be connected through the contacts of the key 380 to grounded battery until the key 380 has been moved to inoperative position. Thus the punch distributor carriage 208 will be moved to its extreme left position as shown in Fig. 1 and just before it reaches that position a slide bar 322 will be moved to the left (Fig. 3) to make contact between contacts 332 and 335 where the machine

will be in the normal position and ready to receive a second problem.

After the punch key 54 has been operated, the operator may immediately start to put a new set of information into the relays 123, while the punch distributor carriage is completing its travel across the contact plate 120, thereby expediting greatly the operation of the machine. As previously described, the keys 13 and 43 to 56 inclusive will be locked in the inoperated position by plate 33 if and whenever the relay distributor brushes approach within two columns on plate 120 of the punch distributor brushes.

In order to permit the perforation of alphabetical information in record cards which are to be used for listing or like operations where it is desired to control printing mechanisms to print other than numerical data, there is provided an alphabetical key board 410 for controlling applicants' perforator in a manner such that combinations of holes may be punched in each column of a record card. This keyboard is provided with a key 411 for each letter of the alphabet and for each of the digits 1 to 9 and the numbers 0, 11 and 12 as well as keys 412, 413 and 414 for controlling spacing, punching and back-spacing respectively.

The alphabetical key board 410 is mounted at the front edge of the base 11 and may be used interchangeably with the key board heretofore described for the perforation of holes representing numbers. The keys 411 are similar to the keys 13, 43, 44, etc., the difference being that the keys 411 representing the letters B, C, D, E, F, H, J, K, L, M, N, P, Q, R, T, U, V, W, X and Y are each provided with an extra contact and control the setting up of information in two relays 123 in each row associated with the keys at the time they are operated. The keys 411 representing the letters A, G, I, O, S and Z control the same relays 123 as do the keys 43, 50, 45, 44, 52 and 13, respectively, and have their contacts connected in parallel with the contacts of the keys 43, 50, 45, 44, 52 and 13, since when cards are to be used for printing control a perforation in the position allotted to the number 11 will cause an "A" to be printed a hole in the 12 position will cause a Z to be printed and the same printing characters are used for the letters G, I, O, and S as are used for the digits 6, 1, 0 and 8, respectively. In like manner the keys 411 representing the numbers 12, 11, 0, 1, 2, 3, 4, 5, 6, 7, 8 and 9 are connected in parallel with keys 13, 43, 44, etc. representing the numbers 12, 11, 0, 1, 2, 3, 4, 5, 6, 7, 8 and 9, respectively, and the contacts of the punch key 413, the space key 412 and the backspace key 414 are connected in parallel with the punch key 54, the space key 55 and the backspace key 56, respectively.

The construction of the keys 411 is such that upon operation of a key all of the contacts of the key will be interconnected and one contact of each key is connected to the conductor 85 leading to ground at 86 and another contact of each key is connected to the conductor 83. The keys 411 representing the letters B, C, D, E, F, H, J, K, L, M, N, P, Q, R, T, U, V, W, X and Y have their other two contacts connected to conductors 59 and 61, 59 and 63, 59 and 65, 59 and 67, 59 and 69, 59 and 71, 59 and 73, 59 and 75, 59 and 77, 59 and 79, 57 and 61, 57 and 63, 57 and 65, 57 and 67, 57 and 69, 57 and 71, 57 and 73, 57 and 75, 57 and 77, and 57 and 79, respectively.

From the foregoing it will be apparent that the keys B, C, D etc. will cause two relays 123 to be locked up in a row of relays each time one of them

is operated and that the keys 411 representing the letters B, C, D, E, F, H, J, K, L, M, N, P, Q, R, T, U, V, W, X, Y will cause the punching of perforations in the 11 and 0, 11 and 1, 11 and 2, 11 and 3, 11 and 4, 11 and 5, 11 and 6, 11 and 7, 11 and 8, 11 and 9, 12 and 0, 12 and 1, 12 and 2, 12 and 3, 12 and 4, 12 and 5, 12 and 6, 12 and 7, 12 and 8, and 12 and 9, hole positions in the rows in which the keys are associated at the time of their operation.

Although this invention has been described in 10 connection with a specific embodiment of a perforating machine, it will be understood that it is capable of many other embodiments, and should be limited only by the scope of the appended claims.

What is claimed is:

1. In an apparatus for punching information in statistical cards, a plurality of groups of storage relays adapted to be energized and held energized for storing information to be punched in a sheet, 20 and means controlled by the energized relays for punching the information stored therein in the sheet and operable under control of some of the groups while information to be punched in a second sheet is being stored in other groups. 25

2. In a perforating apparatus, a plurality of storage relays, means for storing in said relays information to be perforated in one sheet, and means for perforating a sheet in accordance with the stored information while other information is 30 being stored in said storage relays for perforation in another sheet.

3. In a mechanism for marking information in a record, keys representing characters, a plurality of groups of storage relays representing the characters, means controlled by each of the keys for successively associating the keys with each group of storage relays, and means controlled by the storage relays for marking information in one record while other information is being stored in 40 said storage relays for perforation in another record. 35

4. In a mechanism for marking information in record cards, keys representing characters, a plurality of groups of storing means representing 45 characters, means controlled by each of the keys for successively associating the keys with each group of storing means to store information to be marked in a record card, a plurality of marking members, and means for successively associating 50 the marking members with each group of storage relays for marking information in one card simultaneously with the storage by the keys of information to be marked in another card.

5. In a mechanism for marking information in 55 record cards, keys representing characters, a plurality of groups of storage relays adapted to be held energized for storing information, each group representing the characters represented by the keys, means controlled by the keys for associating the keys with each group of storage relays, a group of marking means representing the characters, and means for successively associating the marking means with each group of storage relays for marking information in one card simultaneously with the storage in the storage relays of information to be marked in another card. 60

6. In a mechanism for perforating information in a record, setup means representing characters, storage means representing the characters arranged in columns for maintaining an electrical circuit representing the characters set up, perforating means representing the characters, means for operatively associating the setup means with the storage means to store information in the 65 70 75 80 85 90 95 98

storage means for subsequent perforation in a record, and means for effecting an operative association of the perforating means successively with each column of storage means to perforate a record in accordance with the information stored in the storage means simultaneously with the operation of operatively associating the setup means with the storage means to store information for perforation in a second record.

- 10 7. In a mechanism for marking information in sheets, marking members for marking information in a sheet, means for moving the sheet past the marking members, a plurality of setup means for setting up information for marking in the sheet, storage means for receiving the information from the setup means and for storing said information by maintaining an electrical circuit representative of the information set up, and means movable with the sheet for associating the marking members with the storage means simultaneously with the reception by the storage means of information to be recorded in a second sheet.
8. In a mechanism for marking information in a record, a plurality of groups of electrical contacts, storage means associated with each contact, a group of setup mechanisms, means for associating the group of setup mechanisms with each group of contacts, a group of marking members, and means for successively associating the group of marking members with each group of contacts.

9. In a mechanism for recording information in a record, a plurality of groups of electrical contacts, storage means associated with each contact, a group of setup mechanisms, means for associating the group of setup mechanisms with each group of contacts, a group of recording members, means for successively associating the group of recording members with each group of contacts, and means for releasing the information stored in the storage means after the recording members have been affected by the storage means.

10. In a mechanism for recording information in a record, a plurality of groups of electrical contacts, storage means associated with each contact, a group of setup mechanisms, means for associating the group of setup mechanisms with each group of contacts, a group of recording members, means for successively associating the group of recording members with each group of contacts, means for releasing the information stored in the storage means after the recording members have been associated with the groups of contacts with which the storage means are associated, and means associated with each group of storage means for selectively rendering said releasing mechanism ineffective.

11. In a mechanism for recording information in a record, a plurality of groups of electrical contacts, storage means associated with each contact, a group of setup mechanisms, means for associating the group of setup mechanisms with each group of contacts, a group of recording members, means for associating the group of recording members with each group of contacts, means for releasing the information stored in a storage means after the recording members have been associated with the groups of contacts with which the storage means are associated, and means associated with each group of contacts and operable for rendering the releasing means ineffective with respect to its associated group of storage means.

12. In a mechanism for recording informa-

tion in records, a plurality of groups of contacts, a group of setup mechanisms, means movable over the contacts for associating the group of setup mechanisms with each group of contacts to transmit information to the contacts, a group of recording members, and means movable over the contacts for associating the recording members with each group of contacts to take information from the contacts and transmit it to the recording members.

13. In a mechanism for recording information in records, a plurality of groups of contacts, a storage means associated with each contact, a group of setup mechanisms, means movable over the contacts in one direction for associating the group of setup mechanisms with each group of contacts to transmit information to the contacts, a group of recording members, means movable over the contacts in the said direction for associating the recording members with each group of contacts to take information from the storage means and transmit it to the recording members, and means for moving the movable means over the contacts in the opposite direction and rendering them ineffective during such movement.

14. In a mechanism for recording information in a record, a plurality of electrical contacts arranged in groups, a storage means associated with each contact, a plurality of setup devices corresponding in number to the contacts in each group of contacts for setting up information in the storage means for recording in a record, means controlled by the setup devices for associating the setup devices with each group of contacts to control the operation of the storage means, a recording means operable by the storage means, and means for successively associating the recording means with each group of contacts to cause the recording means to be operated by the storage means through its associated contact while information for perforation in another record is being set up by the setup means.

15. In a mechanism for perforating record cards, a plurality of keys each representing a separate character, a plurality of groups of electrical storage relays each group having a relay therein representing each of the characters represented by the keys, means for successively connecting all the keys to their associated storage relays in each group of storage relays to store information in the storage relays for perforation in a record card, a plurality of perforators corresponding to the characters represented by the keys, means for successively associating the perforators with each group of storage relays for selecting a perforator for actuation in accordance with the information stored in the group of storage relays, and means for advancing a record card step-by-step past the perforators simultaneously with the association of the perforators with the storage relays to perforate information in the record card in accordance with that stored in the storage relays while the keys are being operated to set up information for perforation in a second record card.

16. In a perforating apparatus, a plurality of storage means arranged in columns, a carriage movable with respect to the columns of storage means to store information therein for perforation in a record card, a plurality of perforating members, a carriage movable with respect to the columns of storage means for controlling the perforating members in perforating said card in

accordance with the information stored in the storage means while the storage means is having information stored therein for perforation in another card, and means for coordinating the movement of the carriages to prevent one of them from interfering with the operation of the other one.

17. In a recording apparatus, a plurality of recording members, a reciprocable carriage for controlling the operation of the recording members, means for driving said carriage in a forward direction to control the actuation of the recording members, means for returning the carriage into position to be moved by said last mentioned means, and means actuated by said carriage for controlling the operation of the means for moving the carriage in the forward direction.

18. In a recording apparatus, means for storing information, a plurality of recording members, a reciprocable carriage for controlling the operation of the recording members in accordance with the information stored in said storing means, means for driving said carriage in a forward direction to control the actuation of the recording members, means for returning the carriage, means controlled by the carriage for rendering it ineffective to control the actuation of the recording members during its return movement, and means actuated upon the completion of the return movement for initiating the forward movement.

19. In a recording apparatus, means for storing information, a plurality of recording members, a reciprocable carriage for controlling the operation of the recording members in accordance with the information stored in said storing means, means for driving said carriage in one direction to control the actuation of the recording members, means for returning the carriage, and means controlled by the carriage for rendering the carriage ineffective to control the actuation of the recording members during its return movement.

20. In a perforating apparatus, means for storing information, a plurality of perforating members, a reciprocable carriage for controlling the operation of the perforating members in accordance with the information stored in said storing means, means for driving said carriage in one direction to take from the storage means the information stored therein and transmit it to the perforating members, means for moving the carriage into position to be moved by said last mentioned means, and a slide bar controlled by said carriage for controlling the operation of the means for moving the carriage to take information from the storage means.

21. In a perforating apparatus, means for storing information, a plurality of perforating members, a reciprocable carriage for controlling the operation of the perforating members in accordance with the information stored in said storing means, means for driving said carriage in one direction to take from the storage means the information stored therein and transmit it to the perforating members, means for moving the carriage into position to be moved by said last mentioned means and means for rendering the carriage ineffective to control the perforating members during the movement of the carriage into said position.

22. In a perforating apparatus, means for storing information, a plurality of perforating members, a reciprocable carriage for controlling the

operation of the perforating members in accordance with the information stored in said storing means, means for driving said carriage in one direction to take from the storage means the information stored therein and transmit it to the perforating members, means for moving the carriage into position to be moved by said last mentioned means, means for rendering the carriage ineffective to take information from the storage means during its movement into position to take such information from the storage means, and means for controlling the operation of the means for moving the carriage to take the information from the storing means.

23. In a recording apparatus, a plurality of storage means arranged in columns, means for setting up information in said storage means including a plurality of brushes adapted to successively engage successive columns of storage means, means for successively engaging successive columns of said storage means and controlled by said storage means for perforating a record and clearing the information stored in the storage means, and means for rendering said clearing means inoperative with respect to pre-determined selected columns of storage means.

24. In a perforating apparatus, means for storing information, a plurality of perforating members, a reciprocable carriage for controlling the operation of the perforating members in accordance with the information stored in said storing means, means for driving said carriage in one direction to take from the storing means the information stored therein and transmitting it to the perforating members, means for moving the carriage into position to be moved by said last mentioned means, means for rendering the carriage ineffective to control the perforating members during the movement of the carriage into said position, and a slide bar for rendering the carriage effective to control the perforating members when the carriage arrives in said position.

25. In a perforating apparatus, means for storing information, a plurality of perforating members, a reciprocable carriage for controlling the operation of the perforating members in accordance with the information stored in said storing means, means for driving said carriage in one direction to take from the storing means the information stored therein and transmitting it to the perforating members, means for moving the carriage into position to be moved by said last mentioned means, means for rendering the carriage ineffective to control the perforating members during the movement of the carriage into said position, a slide bar actuated by the carriage and contacts operable by said slide bar for controlling the operation of said means for rendering the carriage ineffective.

26. In a perforating apparatus, means for storing information, a plurality of perforating members, a reciprocable carriage for controlling the operation of the perforating members in accordance with the information stored in said storing means, means for driving said carriage in one direction to take from the storing means the information stored therein and transmitting it to the perforating members, means for moving the carriage into position to be moved by said last mentioned means, a slide bar actuated by the carriage, contacts operable by said slide bar for maintaining the carriage ineffective to control the perforating members until the carriage reaches said position, and other contacts operable by said

slide bar for controlling the operation of the driving means.

27. In an apparatus for entering information in record sheets, means for storing information to be recorded, a recording means, means for rendering the storing and recording means effective simultaneously to store new information for a succeeding sheet and record in a different sheet information previously stored, and means for effecting the automatic recording of predetermined identical information in a plurality of succeeding sheets.

28. In an electric recording system, means for setting up information to be recorded, means electrically connected to the setup means for storing the said information, recording means electrically controlled by the storing means for recording the information in a sheet while additional information is being set up for recording in a succeeding sheet, and electrical control means for determining the areas of the sheets in which information is to be recorded.

29. In an apparatus for punching information in statistical cards, a plurality of groups of stor-

age relays designed to be energized and held energized for storing information to be punched in a sheet, means controlled by the energized relays for punching the information stored therein in a sheet, means for deenergizing said relays after they have controlled the punch, and means for rendering said last mentioned means ineffective to control some of said groups, the means for punching being under control of some of the groups while information to be punched in a 10 second sheet is being stored in other groups.

30. In a punch for statistical cards, a plurality of groups of storage mechanisms, means for setting information to be punched in one card into said storage mechanisms, means for retaining information to be punched in a plurality of cards in said storage mechanisms, and means controlled by said storage mechanisms for punching in a card any of the information stored in the storage mechanisms while information is being set into 20 the storage mechanism for punching in a succeeding card.

HAROLD G. JOHNSTONE.
JOHN C. GATES.
